UNITED STATES PATENT OFFICE.

CHARLES H. WHITE, OF HANFORD, CALIFORNIA.

RAILROAD-CROSSING.

1,374,415.

Specification of Letters Patent. Patented Apr. 12, 1921.

Application filed October 19, 1920. Serial No. 417,969.

To all whom it may concern:

Be it known that I, CHARLES H. WHITE, a citizen of the United States, residing at Hanford, in the county of Kings and State 5 of California, have invented a new and useful Railroad-Crossing, of which the following is a specification.

The device forming the subject matter of this application is adapted to be used at the 10 point where the rails of railroad tracks cross, to the end that the lines may be practically continuous at the point of crossing.

The invention aims to provide novel means for operating the shiftable rail section, so that the same will be alined with rails which are disposed at an angle to each other. Another object of the invention is to provide novel means whereby the friction may be reduced during the operation of the 20 structure. A further object of the invention is to provide novel means whereby a secure seat for the shiftable rail section is provided, when the said rail section is in operative position.

25 It is within the province of the disclosure to improve generally and to enhance the utility of devices of that type to which the invention appertains.

With the above and other objects in view, 30 which will appear as the description proceeds, the invention resides in the combination and arrangement of parts and in the details of construction hereinafter described and claimed, it being understood that, within 35 the scope of what is claimed, changes in the precise embodiment of the invention shown can be made without departing from the spirit of the invention.

In the accompanying drawings:

40 Figure 1 shows in top plan, a device constructed in accordance with the invention; Fig. 2 is a bottom plan; Fig. 3 is a fragmental transverse section; Fig. 4 is a section on line 4—4 of Fig. 3; Fig. 5 is an elevation 45 showing the operating means.

The numeral 1 denotes a casing which may be of inverted cup-shape, a pair of rails 2 projecting from the casing 1, and a pair of rails 3 projecting from the casing 1, rails 50 2—2 and 3—3 being disposed at any desired angle with respect to each other. At their inner ends, the rails 2—2 and 3—3 are supplied with overhanging projections 4. The top of the casing 1 is supplied with arcuate 55 flanges 5.

A shaft 6 is journaled for rotation in the

casing 1 and is vertically movable therein. The upper end of the shaft 6 carries a rail section 7 of sufficient length to extend between the rails 2—2 and 3—3. The rail section 7 is supplied at its ends with extensions 8, each extension being beveled in opposite directions as indicated at 9 in Fig. 4. The shaft 6 is supplied with a squared portion 10 terminating in a reduced tip 11. A pinion 12 is mounted on the squared portion 10 of the shaft 6. A rack bar 14 is mounted for right line reciprocation in the casing 1 and meshes into the pinion 12. A washer 15 is carried by the tip 11 and is held in place by a cotter pin 16 or the like. The numeral 17 denotes a spring of any desired sort, preferably in the form of an arm or slit, the inner end of the spring arm being supplied with a fork 18, straddling the tip 11 of the shaft 6, between the washer 15 and the pinion 12. The outer end of the spring arm 17 is secured to the casing 1, as indicated at 19.

In practical operation, when the rack bar 80 14 is moved endwise, rotation will be imparted to the pinion 12, the pinion rotating the shaft 6, and movement being imparted to the rail section 7, the rail section 7 being placed in alinement with the rails 2—2 or 85 3—3. The rail section 7 abuts against the ends of the flanges 5 and, thus, the rail section is alined with the rails 2—2 or 3—3, as aforesaid. When the rail section 7 is swung out of alinement with the rails 2—2 or 3—3, 90 the extensions 8 ride out from beneath the projections 4. Then, the rail section 7 is set free for vertical movement. The spring 17 exerts an upward pressure on the shaft 6 and raises the shaft, along with the rail section 7, until the rail section no longer is in 95 100 slid engagement with the upper surface of the casing 1. Friction, consequently, is reduced, and the rail section may be swung from one position to another, with less expenditure of effort than would be the case otherwise.

When the rail section 7 approaches alinement with the rails 3—3 or 2—2, the beveled portions 9 of the extensions 8 cooperate with the projections 4, the rail section 7 being crowded downwardly against the action of the spring 17, to a firm seat on the top of the casing 1. Thus, although the rail section 7 may be operated freely, the rail section has a firm bearing when it is in 110 115 operative position.

As shown in Fig. 5, the bar 14 may be

supplied with a rack 75 meshing into a pinion 76 on a shaft 77 journaled in a support 78, the shaft having an operating handle 79.

Having thus described the invention, 5 what is claimed is:—

1. In a device of the class described, a casing provided with pairs of alined rails; a rail section journaled on the casing and movable into and out of alinement with the 10 rails of the respective pairs, the rail section being vertically movable on the casing; means for raising the rail section off the casing; means for swinging the rail section into alinement with the rails of the respective 15 pairs; and interengaging elements on the ends of the rail section and on the rails for forcing the rail section downwardly upon the casing when the rail section is swung into alinement with the rails of either pair.
2. In a device of the class described, a casing provided with pairs of alined rails having projections at their inner ends, the casing being supplied with upstanding flanges; a shaft journaled in the casing and mov- 20 ing vertically therein; a rail section carried by the shaft and having terminal extensions, the extensions and the projections being relatively beveled transversely to facilitate the engagement of the extensions beneath the projections when the shaft is rotated to cause the rail section to abut against the 25
3. In a device of the class described, a casing provided with pairs of alined rails having projections at their inner ends, the casing being supplied with upstanding flanges; a shaft journaled in the casing and movable vertically therein; a rail section carried by the shaft and having terminal 30 extensions, the extensions and the projections being relatively beveled transversely to facilitate the engagement of the extensions beneath the projections when the shaft is rotated to cause the rail section to abut against the

flanges and to aline the rail section with the rails of the respective pairs; a pinion on the shaft and located within the casing; a rack bar slideable in the casing and meshing with 35 the pinion; and a spring carried by the casing and exerting an upward pressure on the shaft.

3. In a device of the class described, a casing provided with pairs of alined rails having projections at their inner ends, the casing being supplied with upstanding flanges; a shaft journaled in the casing and movable vertically therein; a rail section carried by the shaft and having terminal 40 extensions, the extensions and the projections being relatively beveled transversely to facilitate the engagement of the extensions beneath the projections when the shaft is rotated to cause the rail section to abut 45 against the flanges and to aline the rail section with the rails of the respective pairs; means for rotating the shaft; and means for raising the shaft.

In testimony that I claim the foregoing as 55 my own, I have hereto affixed by signature in the presence of two witnesses.

CHARLES H. WHITE.
